[57]

CLAIM

The ornamental design for a sterilization indicator with a transparent portion, as shown.

DESCRIPTION

FIG. 1 is a perspective view showing my new design.

FIG. 2 is a front view showing my new design.

FIG. 3 is a rear view.

FIG. 4 is a left side view showing my new design, the right side being a mirror image thereof; and,

FIG. 5 is bottom view showing my new design, the top view being a mirror image thereof.

The broken lines shown in FIGS. 1-5 are for illustrative purposes only and form no part of the claimed design.
